JOHN H. KAPPELHOFF, OF NEW YORK, N. Y.

Design No. 3,697, dated October 5, 1869.

DESIGN FOR A MUFF.

The Schedule referred to in these Letters Patent and making part of the same.

To all whom it may concern:

Be it known that I, JOHN H. KAPPELHOFF, of the city, county, and State of New York, have invented a new and original Design for Muff; and I do hereby declare the following to be a full, clear, and exact description thereof, which will enable those skilled in the art to make and use the same, reference being had to the accompanying drawing, forming part of this specification.

The drawing represents an elevation of this design.

This design relates particularly to the back of a muff, which is ornamented by a flap, A, embossed

with flowers and foliage, and provided with a raised bead, a, which encloses a mirror, b.

By these ornaments a handsome and distinguishing appearance is given to my muff.

What I claim as new, and desire to secure by Letters Patent, is—

The design for a muff, as shown and described.

This specification signed by me, this 6th day of September, 1869.

Witnesses: JOHN H. KAPPELHOFF.
